UNITED STATES PATENT OFFICE.

HENRY O. WESTENDARP, OF LYNN, MASSACHUSETTS, ASSIGNOR TO GENERAL ELECTRIC COMPANY, A CORPORATION OF NEW YORK.

HYDROCARBON-ENGINE.

1,107,636.

Specification of Letters Patent. Patented Aug. 18, 1914.

Application filed April 7, 1910. Serial No. 553,937.

To all whom it may concern:

Be it known that I, HENRY O. WESTENDARP, a citizen of the United States, residing at Lynn, county of Essex, State of Massachusetts, have invented certain new and useful Improvements in Hydrocarbon-Engines, of which the following is a specification.

The present invention relates to hydrocarbon engines and more specifically to the type known as a two-cycle engine, and has for its object to improve their construction and operation, particular reference being made to the production of an engine which will operate at constant speed under conditions of varying load without changing the point of ignition.

I further aim to provide an engine in which there is no danger of back-firing in the crank chamber.

20 In the accompanying drawings which illustrate embodiments of my invention, Figure 1 is a sectional view of a three port, two-cycle hydro-carbon engine; Fig. 2 is a view of a similar engine slightly modified as to the means for controlling the passage of pure air from the crank chamber to the carburetors; Figs. 3 and 4 are respectively a side elevation and plan view showing my invention applied to a multi-cylinder engine; Figs. 5, 6 and 7 are detail views illustrating the valves for controlling the supply of air to the crank chamber; Fig. 8 is a side view showing the connections between the governor and the valve mechanism; and Fig. 9 is a partial sectional view of the carburetor.

1 indicates the base of the machine, 2 a closed crank chamber having covered openings 3 and 4, by means of which the interior mechanism may be examined. The casting forming the crank chamber may be formed integral with the cylinder 5 or separate castings may be employed and suitably united. This will depend largely upon the size of the engine and the purpose for which it is intended. Mounted in suitable bearings is a shaft 6 having a crank 7. This crank is connected by a rod 8 and pin 9 to the trunk piston 10, the latter reciprocating within the cylinder 5. The piston is provided with suitable packing rings 11. The lower end of the cylinder opens into the crank case and the upper end is provided with a chamber 12 in which the firing takes place. The

diameter of this chamber is somewhat greater than that of the cylinder so as to avoid machine work. The finish of the cylinder stops at the shoulder 13. Located in the top of the cylinder wall or in any other suitable place is an ignition plug 14 that is supported in the cap 15, the latter being secured in place by an annular nut 16 that is threaded into the outer wall 17 of the cylinder. Between the outer and inner walls of the cylinder is a space or chamber 18 to receive water or other cooling fluid. The cylinder is provided with one or more admission ports 19 through which passes a mixture of air and combustible, and with one or more exhaust ports 20 which communicate with an exhaust conduit 21, the latter being formed in a separate casting, in the present illustration of my invention, that is bolted to a finished face on the side of the cylinder. Both the admission and exhaust ports are controlled in their operation by the piston 10. The piston is provided with a baffling device 22 to direct the incoming mixture of air and combustible and to prevent it from passing directly out of the exhaust ports 20 when the latter are opened.

The supply of air to the closed crank chamber is admitted and controlled by the following means: A passage 23 is formed in the same casting with the exhaust conduit, 85 which passage largely surrounds the exhaust conduit so that air passing through the inlet passage into the crank chamber will be heated to a greater or less extent. Located in the passage 23 is a plug 24 containing an air passage and also a valve 25 made somewhat after the fashion of a stove damper, Figs. 5, 6, and 7, so that the admission of cold air can be controlled. The cold air openings 26 are controlled by the valve 25 and the latter is actuated by a handle 27. Air is admitted to the crank chamber by the port 28 that is controlled by the movements of the piston 10. The piston is provided with one or more ports 29 that register with the port or ports 28 when the piston is in its raised position *i. e.* at the beginning of the firing stroke. The piston is provided with a discharge port 30 for the air, that is arranged to register with a port 31 in the lower end of the cylinder or extension thereof when the piston is in its lowest position as shown. When the piston is in a position

- shown, the air which has been compressed by the downward stroke of the piston is free to pass through the ports 30 and 31 to the throttle valve and carbureter. The piston 5 is made long enough to cover the port 31 during the movement of the piston away from the crank chamber so that the reduction of the pressure in the chamber cannot exert a suction action on the carbureter.
- 10 Bolted or otherwise secured to one side of the cylinder is a carbureter 32 comprising a casting containing a chamber 32^a in which is maintained a supply of hydro-carbon at a constant or approximately constant level.
- 15 Extending through this chamber is a nozzle or throat 33 containing one or more orifices 34 through which the hydro-carbon is drawn into the gap 34^a by the reduction of pressure in the nozzle 33 caused by the air flowing 20 through said nozzle at an increased velocity and is entrained with the supply of pure air from the crank chamber. In other words, mixing of the air and fuel takes place at the nozzle 33. The nozzle communicates by a 25 passage 35 with the admission port 19 in the cylinder.

Situated below the carbureter is a throttle valve 36 that is located in the short passage 37 and controls the flow of pure air from the 30 closed crank chamber to the carbureter. This valve is provided with a stem that extends through the casing and to which is connected an arm 38, the latter being controlled as to its movements by a suitable 35 speed governor driven by the main shaft 6 of the engine. The valve can be manually controlled if desired for some forms of service. Mounted on the main shaft is a 40 suitable fly wheel.

45 My improved engine is designed more especially for driving dynamo electric machines at constant speed under widely varying conditions as to load but I do not, however, limit myself to this particular application.

The operation of my improved engine is as follows: Assuming the parts to be in the position shown, the pure air which was admitted by the passage 23 and port 28 has 50 been compressed in the closed crank chamber and is now free to pass through the ports 30 and 31, passage 37 and valve 36 to the carbureter. The action of the air as it passes through the carbureter entrains a 55 certain amount of hydro-carbon fuel and carries it through the passage 25 and discharges it by the port 19 into the interior of the cylinder space and chamber 12, as indicated by the arrows. As the crank 7 60 moves upward, the port 31 is closed. The admission and the exhaust ports 19 and 20 are also closed and the charge of combustible thus trapped is compressed to the end of the stroke when said charge is fired by means 65 of the ignition plug 14 which drives the

piston downward. At or about the time the firing takes place, the end of the piston has uncovered the port 28 and, owing to the vacuum created by the upward movement of the piston, pure air enters by way of the 70 passage 23, or by the passage 23 and ports 26 into the interior of the pump or crank chamber and is thereafter compressed on the downward piston stroke.

On account of the arrangement of the 75 ports and the piston I am able to dispense with cams and separately operated valves, thereby simplifying the engine as a whole. It will be noted that the passage beginning at the port 31 and terminating at the port 19 is extremely short and that it is free from 80 pockets that might trap some of the mixture. By locating the throttle valve 36 in the passage 37 I am able to regulate the supply of air to the carbureter to a nicety, 85 and by arranging the parts as shown I avoid admitting a charge of fluid into the crank chamber where it is liable to ignition by back fire with objectionable results. Further by my improved arrangement, a supply 90 of pure air under constant pressure is always available for the carbureter. By throttling said supply the amount of air which passes through the carbureter may be accurately proportioned to the load on the 95 engine, and as the supply of pure air varies so also will the supply of hydro-carbon. By keeping the fluid out of the crank chamber I avoid troubles incident to starting in cold 100 weather when the fuel would condense to a greater or less extent in the chamber until after the engine was heated.

In Fig. 2 I have shown a somewhat similar arrangement except that the supply of 105 pure air for the carbureter is under the control of a cut-off valve 40. This valve, in addition to acting as a cut-off valve for the air, also acts as a throttle valve to control the amount of pure air that passes to and through the carbureter. The valve is of the 110 oscillating type and is provided with an arm which is connected by the rod 41 with a bell-crank lever 42, the latter being pivotally supported on the crank case. One end of the lever is provided with a roller 43 that 115 rests on the cam 44, the latter being splined on and driven by the main shaft 6. Mounted on the shaft is a beveled gear 45 that meshes with a pinion 46, the latter being connected to a vertical shaft 47 that drives the speed governor 48, Figs. 2 and 8. The speed governor is connected by suitable means including a fork 49 with the cam 44, and as the speed of the main shaft changes the cam is moved axially on said shaft to 120 vary the interval of time on each stroke that the throttle valve 40 is opened. It will be observed that the cam 44 has a flattened portion on which the roller 43 is now resting so that the valve 40 will be opened and closed 125 130

once for every revolution of the shaft. As before stated the cam is so shaped that its position on the shaft with respect to the roller 43 determines the period in each stroke that the valve 40 is opened. The other features of construction of these figures are the same as those of Fig. 1 and hence further description seems unnecessary.

In Figs. 3 and 4 I have shown my invention applied to a multi-cylinder engine wherein the cylinders, pistons, crank case, etc. are arranged as before. Connecting the pure air ports 37 of the previous figures is a conduit 50. This conduit communicates with the carbureter 32 and between it and said conduit is the throttle valve 36. Connecting the fuel admission ports 19 of the previous figures is a conduit 51. In order to insure equal supplies of fuel to the various cylinders by making the resistance to flow of the mixture the same or substantially so in all cases, the carbureter is connected to the supply pipe 52 and the latter is in turn connected to the conduit 51 at two points between the cylinders. It will be noted that the distance between the point of connection of the conduit and supply pipe and the cylinders is the same in all cases, and hence the resistance to flow of the mixture will be the same. The cylinders are connected to the common exhaust conduit 53, and formed in the outer wall of the conduit are air inlet passages 23.

Since the theory of operation of my improved engine has been already set forth, repetition as to the multi-cylinder type seems unnecessary.

In accordance with the provisions of the patent statutes, I have described the principle of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is,—

1. In a two cycle engine, the combination of a piston and a cylinder having admission and exhaust ports both of which are covered and uncovered by the piston, a main shaft driven by the piston, a carbureter, a chamber in which air is compressed by the piston, inlet means for admitting air from the atmosphere to said chamber, an outlet port in the cylinder for the air from the chamber, conduit means for connecting the port to the carbureter and the carbureter to the admission port aforesaid, a port in the piston which communicates with said outlet port when the piston is at substantially the end of its outward stroke, said piston at other times closing said outlet port so as to prevent the suction of the pump from affecting the carbureter, a valve for throttling the

passage of air from the chamber into the carbureter and a means for controlling the valve.

2. In a two-cycle engine, the combination of a piston and a cylinder, a main shaft connected to and moved by the piston, a closed crank chamber communicating with the cylinder into which air is drawn and compressed by the piston, inlet and outlet ports in the cylinder for the air that are controlled by the piston, admission and exhaust ports that are also controlled by the piston, a carbureter connected with the air outlet port and the admission port, the piston covering the outlet port so that the suction produced by the movement of the piston away from the crank chamber does not affect the carbureter, a throttle valve located in the connection between the crank chamber and the carbureter, and means for actuating the throttle valve.

3. In a two-cycle engine, the combination of a piston and a cylinder, a main shaft connected to and moved by the piston, admission and exhaust ports in the sides of the cylinder intermediate its ends that are controlled by the piston, a closed crank chamber into which air is drawn and compressed by the piston, inlet and outlet ports in the cylinder for the air that are controlled by the piston, the inlet port being arranged adjacent the exhaust port, a conduit for the exhaust products of combustion that is attached to the side of the cylinder, said conduit being in open communication with the exhaust port and provided with a passage which receives air at one end, leads it along the wall of the conduit to be heated thereby and delivers it to the inlet port, a controllable inlet for admitting cold air to said passage at a point intermediate its ends, a carbureter adjacent the cylinder into which fuel is drawn by the action of the air flowing through it, conduits connecting the carbureter with the air outlet port and the port admitting the explosive mixture to the cylinder, and a throttle valve in one of said conduits for regulating the flow of air from the crank chamber into the carbureter.

4. In a two-cycle engine, the combination of a piston and a cylinder, a carbureter, a chamber in which air is compressed by the piston to furnish a supply of compressed air to the carbureter, a combined cut-off and throttle valve located between the chamber and the carbureter for cutting off the supply of air at some point in the movement of the piston, admission and exhaust ports in the cylinder which are controlled by the piston, the admission port being connected to the carbureter, a port admitting air to the chamber which is also controlled by the piston, a main shaft driven by the piston, a cam driven by the shaft for opening and closing said valve once during each revolution of

the shaft, a speed governor driven by the shaft, and means actuated by the governor for changing the position of the cam to vary the period that said valve is open during each revolution of the shaft.

5. In a multi-cylinder two-cycle engine, the combination of a plurality of pistons and cylinders, a main shaft connected to the moved by the pistons, pump chambers in 10 which air is compressed by the pistons, a conduit connected to the outlets of all of the chambers, a carbureter connected to the conduit, a valve located between the conduit and the carbureter for controlling the supply 15 of air thereto, fuel admission ports for the

cylinders, a conduit connected to the ports, supply piping connecting the carbureter with the conduit at points intermediate the cylinders so that the resistance to flow of the gases to each of the cylinders is substantially 20 the same, exhaust conduit means for the cylinders, and means for admitting air to the pump chambers.

In witness whereof, I have hereunto set my hand this fifth day of April, 1910.

HENRY O. WESTENDARP.

ROBERT SHAND.

Copies of this patent may be obtained for five cents each, by addressing the "Commissioner of Patents,
Washington, D. C."

It is hereby certified that in Letters Patent No. 1,107,636, granted August 18, 1914, upon the application of Henry O. Westendarp, of Lynn, Massachusetts, for an improvement in "Hydrocarbon-Engines," an error appears in the printed specification requiring correction as follows: Page 4, line 8, for the article "the" read *and*; and that the said Letters Patent should be read with this correction therein that the same may conform to the record of the case in the Patent Office.

Signed and sealed this 29th day of September, A. D., 1914.

[SEAL.]

R. F. WHITEHEAD,
Acting Commissioner of Patents.
